UNITED STATES PATENT OFFICE.

CLAUDE J. SQUIRES, OF THREE RIVERS, MICHIGAN.

FUNNEL.

979,807.

Specification of Letters Patent. Patented Dec. 27, 1910.

Application filed February 11, 1910. Serial No. 543,357.

To all whom it may concern:

Be it known that I, CLAUDE J. SQUIRES, a citizen of the United States of America, residing at Three Rivers, in the county of St. Joseph and State of Michigan, have invented certain new and useful Improvements in Funnels, of which the following is a specification, reference being had therein to the accompanying drawings.

10 My invention relates to funnels and has for its object to provide a new and improved means for automatically closing the discharge thereof when the liquid within the receptacle being filled rises to a predetermined height, and consists in the peculiar construction and arrangement of parts as more fully hereinafter described and pointed out in the claims.

20 In the drawings—Figure 1 is a sectional perspective view of a funnel embodying my invention; and Fig. 2 is a modification thereof.

The funnel A comprises the usual inverted cone-shaped body B and the discharge nozzle C extending from the small end thereof. Positioned within the body, in close proximity to the junction of the same and the discharge nozzle, is a transverse partition D which is provided with an aperture E, and F is a valve, preferably of the ball type, controlling said aperture; the partition being adapted in the closed position of the valve to cut off communication between the portion of the body above the partition 35 and the discharge nozzle.

G is a float for automatically closing the valve when the liquid within the vessel being filled rises to a predetermined level and, in order that the liquid discharging from the 40 funnel nozzle will not affect the operation of the float, the latter is positioned out of the path of the funnel discharge. Thus, as shown, the float G is preferably made cylindrical and loosely sleeved upon the extension of the nozzle, the latter thereby serving as a guide rod for the float.

The connection between the float and valve comprises rods H and I each having one of their ends connected respectively to 50 the float and the valve, and having their other ends pivotally connected to a lever J, which is pivoted at a point equidistant its ends to a lateral extension K of an angle arm L mounted upon the interior of the 55 body.

M and N are vertically-aligning apertures formed in the transverse partition and the body portion of the funnel, and O is an open-ended tube forming a guide for the rod H, and having its upper end positioned slightly below the plane of the funnel top. The lower end of this tube extends through the aperture in the transverse partition and is secured to the funnel body with the bore of the tube in alignment with the aperture N. The joints between the tube O and the transverse partition and the tube body are sealed as by soldering, so as to prevent the liquid within the funnel from leaking through the apertures M N. Surrounding the float and secured to the contracted portion of the funnel body is a cylindrical casing Q forming a guard for the float. In order that the lower end of the casing will not be hermetically sealed by the liquid within the vessel being filled, and thereby prevent the raising of the float, a vent is formed in the casing, preferably by slitting the latter longitudinally, as at R.

S are lugs secured to the lower end of the guard for limiting the downward movement of the float. As the length of the necks of cans, bottles, and other receptacles vary, a ring R' is adjustably secured upon the casing Q and is adapted, when the funnel is in use, to rest upon the neck of the receptacle.

S' is a clamping screw for securing the ring in its different positions of adjustment. If desired, a handle, as T, may be secured to one end of the lever K for raising or lowering the valve.

The valve and float are made substantially the same in weight, so that when the valve is moved toward or from its seat, the balanced connections between said members 95 will retain the valve in its adjusted position.

In use, the funnel nozzle is inserted within the neck of the receptacle to be filled, such as the bottle U, and the ring R adjusted to permit the nozzle to project within the bottle the desired distance. The operator then moves the valve from its seat by pressing the handle T downward and fills the receptacle in the usual manner. When the liquid within the receptacle rises sufficiently to raise the float, the rod H will actuate the lever J, and, through the medium of the rod I, lower the valve to its seat.

For the purpose of guiding the valve to and from its seat, the rod I engages a guide

bracket V upon the inner wall of the funnel, while in the modification shown in Fig. 2 the transverse partition D' is formed concave, which further assures the correct seating of the valve.

What I claim as my invention is:

1. In a funnel, the combination with the body portion and the discharge nozzle, of a valve controlling the discharge, a float for actuating said valve loosely sleeved upon said nozzle, and an operative connection between said valve and float, for the purpose described.
2. In a funnel, the combination with the body portion and the discharge nozzle, of a vented guard surrounding said nozzle, a valve for controlling the discharge, and a float for actuating said valve positioned intermediate the guard and nozzle, and an operative connection between said valve and float, for the purpose described.
3. In a funnel, the combination with the body portion and the discharge nozzle, of a valve controlling the discharge, a float for actuating said valve loosely sleeved upon said nozzle, a cylindrical guard encircling said float and nozzle, and secured to the body; and a connection between the float and valve.
4. In a funnel, the combination with the body portion and the discharge nozzle, of a valve controlling the discharge, a float for actuating said valve loosely sleeved upon said nozzle, a cylindrical guard encircling said float and nozzle and secured to the body, a connection between the float and valve, and

means carried by the guard for limiting the downward movement of the float.

5. In a funnel, the combination with the body portion and the discharge nozzle, of a transverse partition positioned within the funnel body having an aperture therein, a valve controlling said aperture, a float sleeved upon said nozzle for automatically closing said valve, a link pivoted upon the float body, a rod secured to said float and extending upward through the funnel body and said transverse partition, and pivotally secured to one end of said link, and a connection between the other end of the link and the valve.

6. In a funnel, the combination with the body portion and the discharge nozzle, of a transverse partition positioned within the funnel body having an aperture therein, a valve controlling said aperture, a float sleeved upon said nozzle for automatically closing said valve, an open-ended tubular member having its upper end positioned in proximity to the funnel top and having its lower end extending through said transverse partition and secured to the funnel body, and a connection between said valve and float, including a rod secured to the float extending upward through said tubular member.

In testimony whereof I affix my signature in presence of two witnesses.

CLAUDE J. SQUIRES.
